UNITED STATES PATENT OFFICE

172,994

SET OF GAME PIECES

Eric G. Shalkhauser, Washington, Ill.

Application February 10, 1954, Serial No. 28,956

Term of patent 14 years

(Cl. D34—5)

To all whom it may concern:

Be it known that I, Eric Shalkhauser, citizen of the United States, residing in Washington, in the county of Tazewell and State of Illinois, have invented a new, original, and ornamental Design for a Set of Game Pieces, of which the following is a specification, reference being had to the accompanying drawing, forming a part hereof.

Fig. 1 is a side elevational view of one game piece in a set of game pieces, showing my new design;

Fig. 2 is a side elevational view of the game piece shown in Fig. 1;

Fig. 3 is a side elevational view of another game piece in the set;

Fig. 4 is a top plan view of the game piece shown in Fig. 3;

Fig. 5 is a side elevational view of still another game piece in the set; and

Fig. 6 is a top plan view of the game piece shown in Fig. 5.

I claim:

The ornamental design for a set of game pieces, as shown.
